Attorney

UNITED STATES PATENT OFFICE

AUGUST J. PACINI, OF CHICAGO, ILLINOIS, ASSIGNOR TO CHARLES M. RICHTER, OF CHICAGO, ILLINOIS

METHOD OF REDUCING THE POISONOUS EFFECTS OF NICOTINE AND THE PRODUCT THEREOF

Application filed May 8, 1929. Serial No. 360,256.

This invention relates to the reduction of the physiologically poisonous or toxic effects of nicotine, and with regard to certain more specific features to such reduction without removal from a substance of the nicotine per se.

Among the several objects of the invention may be noted the provision of means for treating substances having a nicotine content such that the said nicotine content will be rendered less toxic, the treatment being accomplished without actually removing the substance constituting the nicotine; the provision of means of the class described which do not substantially alter the other physical and/or chemical characteristics of the nicotine-bearing substance, whereby the normal enjoyment or use of the substance, tobacco for example, is not interfered with. Other objects will be in part obvious and in part pointed out hereinafter.

The invention accordingly comprises the elements and combinations of elements, steps and sequences of steps, features of synthesis and arrangements of parts which will be exemplified in the description hereinafter and the scope of the application of which will be indicated in the following claims.

In the accompanying drawings, in which is shown one of various possible embodiments of the invention,

Fig. 1 is a diagrammatic view illustrating a test;

Fig. 2 is a diagrammatic view illustrating a method of treatment;

Fig. 3 is a view similar to Fig. 2, illustrating a modified form of treatment; and,

Fig. 4 is a view similar to Fig. 2 illustrating another modification.

Similar reference characters indicate corresponding parts throughout the several views of the drawings.

Hereinafter, as an example and for the purpose of demonstrating the effect of this invention, tobacco will be referred to as the substance in which the poisonous effects of nicotine are to be reduced and/or neutralized. It is to be understood that other nicotine-bearing substances, or even nicotine itself, may be similarly treated with the same or similar results.

It is also to be understood that the term "tobacco" as used herein refers to cured or aged tobacco, such as is generally utilized in commerce for the manufacture of cigars, cigarettes, pipe tobacco and the like.

Before describing the invention, the following should be noted: The quantity of nicotine present in tobacco, as determined by the usual methods of assay (non-biological) is not a criterion of the toxicity of the tobacco, inasmuch as the condition in which the nicotine exists is the determining criterion for determination of its physiological effects. Thus according to the ordinary tests, two samples of tobacco may have equal amounts of nicotine but on the other hand be unequally toxic, because in one, the condition of the nicotine is different from the same amount in the other. As illustrative of this fact in a different field, it may be noted that the determination of the amount of ergosterol in a fat is not a measure of the amount of vitamin D in that fat, although vitamin D and ergosterol answer the same chemical tests. The reason is, as in the case of the present invention, that the distinguishing criterion is biological. Thus an assay of tobacco before and after the treatment outlined herein appears to provide the same amount of nicotine by ordinary tests, yet biologically the effects of this nicotine are different.

As an example of what is referred to above, I have found that nicotine produces definite pharmacologic effects when administered to different animals. The effect is observed whether the nicotine be administered in its alkaloidal form, or whether it be administered in its natural occurrence as tobacco.

The characteristic action of nicotine may be noted by its effect upon the frog, the animal evidencing a folding of the hind legs over the back. This action is sufficiently characteristic to make it possible to distinguish nicotine from its related poisons, and is sensitive to the point where the presence of about $\frac{1}{10}$ mg. of nicotine may be demonstrated.

In order to estimate with relatively accuracy the comparative toxicity of untreated tobacco and tobacco treated by the invention

set out herein, a Bell jar 1, (Fig. 1), tubulated, is fitted with a doubly perforated stopper 3. A bent tube 5 passes through the stopper 3 and ends just below it. A thistle funnel 7 passes through the second perforation and reaches nearly to the bottom of the jar. The jar is placed on a glass plate 9 and sealed reasonably air-tight by coating the contact between the jar and the plate with petroletum. A frog 11 is introduced into the Bell jar and the jar is placed in its position on the plate. The thistle funnel is filled with tobacco 13, lighted, and the smoke is aspirated into the jar. Depending upon the amount of smoke consumed, and the time required for the symptoms of toxicity to appear, it is possible to estimate with relative accuracy the comparative toxicity of a treated and an untreated tobacco. By this method, tobacco for cigarettes, pipes, cigars, snuff and other purposes may be accurately tested for toxicity of nicotine independently of the ordinary chemical tests for nicotine.

Another method for the determination of the loss in the toxic quality consists in passing by bubbling the smoke obtained from a weighted amount of tobacco through water, and injecting an aliquot part into any suitable animal prepared by the usual physiological methods for the determination of blood pressure, nicotine being the only constituent of smoke that raises the blood pressure. The amount of rise is a measure of the amount of detrimental effect of the nicotine. Bubbling can be effected by placing a glass of water around the lower end of the funnel tube 7 (see dotted lines Fig. 1).

In regard to my invention per se, I have found that nicotine ordinarily absorbs in the ultraviolet region at $280 \text{ m}\mu$., and in more diluted concentrations, at $270 \text{ m}\mu$. I have discovered that the absorption of nicotine in this region is not selective, but is general.

I have discovered further that the exposure of nicotine, or of tobacco leaf, cut or uncut, to ultraviolet radiation of wavelengths of from 4000 Angstrom units to the limit of a mercury vapor lamp in quartz (approximately 1800 Angstrom units), or the exposure of nicotine to infra-red radiation peaked especially in the region of $2.5 \text{ m}\mu$. results in the toxicity of the nicotine being diminished. I have demonstrated this repeatedly in the manner set out above, that is, by biological tests. Thus it will be seen that tobacco when treated either by ultra-violet rays or infra-red rays loses much of its toxicity. This loss of toxicity is a fact as shown by the biological assays, although the ordinary physical and/or chemical assays show that tobacco before and after treatment appears to have the same amount of nicotine per se. The conclusion is that the condition or biological characteristics or the like of the nicotine have been changed after

treatment, although apparently the nicotine remains as a substance.

The above effect is exceedingly desirable, because it is preferable that the tobacco of commerce retain all of its original constituents in order to be perfectly salable. That is to say, tobacco which has the nicotine content actually removed, such as by washing or the like, is not as salable as that which has the nicotine content left therein in a harmless form. By means of this invention the original physical makeup of the tobacco (or other substance) is unchanged but the advantage is had that the nicotine is rendered substantially harmless and at least less toxic.

Referring now to the method of treatment, the cut, sliced, minced or otherwise prepared tobacco is exposed in thin layers to infra-red rays, for example in the following fashion (Fig. 2): A layer 13 of tobacco loosely textured is passed under suitable conveying methods so as to course underneath one or more infra-red generators. The number of generators is determined by the amount of tobacco to be treated, the area undergoing exposure, and the degree of detoxification sought. The drawing shows two generators 15 exposing the tobacco layer 13. The layer 13 is carried on a moving conveyor 17 from a supply 19 to a receiver 21.

In passing under the infra-red generators whose radiation is detected in the region of $2.5 \text{ m}\mu$, the tobacco undergoes a general absorption of infra-red radiation which, in the presence of air, results in a change in the nicotine. The change is apparently one of oxidation, the nicotine becoming nicotinic acid. It is to be understood that this explanation of the phenomenon may not be the ultimate one for the radiation changes may impart other and as yet unknown characteristics which have thus far eluded detection. The fact is that the toxicity of the nicotine content is greatly lowered by this treatment.

The treatment can be accomplished also in a similar fashion by passing the tobacco under mercury vapor lamps in quartz 23, by which method, the mercury vapor lamp in quartz replaces the infra-red generator (see Fig. 3).

A change may also be effected in the case of nicotine by means of intensified visible light, such as that obtained from an incandescent lamp 25 (Fig. 4) with a range of wavelengths of from $\lambda 302 \text{ m}\mu$ to $\lambda 1400 \text{ m}\mu$. These are radiations usually emitted by the general type of tungsten, incandescent lamp inclosed in glass. I have discovered that nicotine freshly prepared from tobacco undergoes a color change when exposed to the radiations mentioned in the presence of air, and I have discovered further that this color change is attended by a marked reduction in the toxicity of the nicotine. By the term intensified is meant herein light of intensity

greater than that to which tobacco or the substance being treated is normally exposed.

If freshly prepared nicotine is placed in a pyrex test tube and this be suspended in the path of the light furnished by a search-light operating with a 1000 watt Mazda lamp, the color of the nicotine changes quickly, and coincident with the color change the toxicity is lessened.

In all the examples above enumerated it is understood that the increase or the decrease of light intensity will involve corresponding changes in the time of exposure, the distance from the light source to the nicotine or the nicotine-containing material, and other obvious photochemical factors.

The examples are merely illustrative and are not meant to limit and/or restrict the discovery to the factors of irradiation outlined. The examples indicate that applied mercury vapor radiation, applied visible light radiation and applied infra-red radiation are all capable of occasioning such changes in nicotine as to reduce its toxicity, without necessarily reducing its apparent physical and/or chemical content in tobacco when determined by the ordinary present day methods. The change results in a biological differentiation.

In view of the above, it will be seen that the several objects of the invention are achieved and other advantageous results attained.

As many changes could be made in carrying out the above constructions without departing from the scope of the invention, it is intended that all matter contained in the above description shall be interpreted as illustrative and not in a limiting sense.

I claim:

1. The method of treating cured tobacco containing toxic nicotine which comprises artificially irradiating said tobacco, to reduce the toxicity of the nicotine content of said tobacco, and substantially maintaining said nicotine content unaltered.

2. The method of treating cured tobacco containing toxic nicotine which comprises subjecting the same to artificial ultra-violet irradiation for a sufficient length of time to detoxify the nicotine content of said tobacco, and substantially maintaining said nicotine content unaltered.

3. The product comprising irradiated cured tobacco, the nicotine therein being detoxified but without substantial alteration otherwise in its essential characteristics.

In testimony whereof, I have signed my name to this specification this 10th day of April, 1929.

AUGUST J. PACINI.

Certificate of Correction

Patent No. 1,754,117.

Granted April 8, 1930, to

AUGUST J. PACINI

It is hereby certified that error appears in the printed specification of the above-numbered patent requiring correction as follows: Page 2, line 120, for " $\lambda 302 \mu$. to $\lambda 1400 \mu$," read $\lambda 302 m\mu$. to $\lambda 1400 m\mu$.; and that the said Letters Patent should be read with this correction therein that the same may conform to the record of the case in the Patent Office.

Signed and sealed this 14th day of July, A. D. 1931.

[**SEAL.**]

M. J. MOORE,
Acting Commissioner of Patents.
